UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,572, dated August 21, 1894.

Application filed July 28, 1894. Serial No. 518,890. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls of roccoco style placed at certain 10 distances apart and forming panels which contain a shell like ornament and a group of flowers and leaves as represented in the accompanying drawing. The ornamental scrolls also form small panels which are filled 15 with lattice work as shown and form part of the design. The border or upper portion of the design is composed of ornamental scrolls arranged horizontally and forming an open

panel in which are placed two shell like ornaments with groups of flowers and leaves; 20 the spaces between the ornamental scrolls and the top and bottom edges of the border being filled with lattice work as shown in the drawing.

What I claim is—

1. The design for wall paper herein shown and described.
2. In the design for wall paper the border herein shown and described.

Witness my hand this 26th day of July, 30 1894.

CHARLES BOOZE.
